HYDRAULIC PALLET LIFT TRUCK

George J. Davis, Atlanta, Ga.

Application August 31, 1956, Serial No. 607,329

2 Claims. (Cl. 254—10)

This invention relates to lift trucks.

It is an object of the present invention to provide a hydraulic pallet lift truck particularly adapted for storage warehouses and which has at least a 3,000 pound capacity.

It is another object of the present invention to provide a hydraulic pallet lift truck of the above type which is operated by a foot pedal and wherein the device includes heavy springs for lowering the lift rapidly.

Other objects of the invention are to provide a hydraulic pallet lift truck bearing the above objects in mind, which is of simple construction, has a minimum number of parts, is inexpensive to manufacture and efficient in operation and use.

For other objects and for a better understanding of the invention, reference may be had to the following detailed description taken in connection with the accompanying drawing, in which:

Figure 1 is a top plan view of a preferred embodiment of the present invention;

Fig. 2 is a side elevational view thereof showing in phantom the raised position of the sub-platform;

Fig. 3 is a vertical sectional view taken along the line 3—3 of Fig. 1;

Fig. 4 is a view looking along the line 4—4 of Fig. 3 with the housing removed;

Fig. 5 is a vertical sectional view taken along the line 5—5 of Fig. 1; and

Fig. 6 is a vertical sectional view taken along the line 6—6 of Fig. 5.

Referring now more in detail to the drawing, a U-shaped main frame indicated generally at 10 is provided and includes a U-shaped end plate 11 (Fig. 4) having the braces 12 and which is longitudinally spaced and parallel to the end plate 13, suitable brace means being provided for connecting the plates 11 and 13.

The main frame 10 includes a pair of laterally spaced, parallel side portions 14 of U-shaped cross section fixedly connected at one end to the end portion of the frame 10 and supported at their ends remote from the plates 13 by the wheels 15 and axle 16 (Fig. 5), ball bearing mountings being employed.

The platforms 17 are fixedly mounted on the ends of the plate 11 and support the U-shaped handle 18 as well as mounting therebelow the casters 19 of ball bearing construction. Braces 20 reinforce the connection of the handle 18 to the platform 17, while the braces 21 reinforce the connection of the platforms themselves to the plate 13.

A supporting plate 22 is mounted intermediate the plates 11 and 13 (Fig. 3) being inclined upwardly and forwardly and mounting thereon the hydraulic jack indicated generally at 23. The hydraulic jack 23 includes the foot pedal 24 as well as the release pedal 25, being of conventional construction.

A transverse shaft 26 is fixedly mounted at the upper end of the jack and is urged downwardly by the coil springs 27 having their lower ends connected to the base plate 22.

A sub-platform is provided and includes a pair of side members 28 of inverted U-shaped cross section hav-

2

ing bevelled ends 29 to facilitate their insertion under the object to be lifted, the side portions 28 being adapted to fit downwardly in nesting relationship over the side portions 14 of the main frame 10 (Fig. 5). The side portions 28 of the sub-platform are connected at their other end by the transverse plate 30 as well as the braces 31 and 32.

A pair of laterally spaced links 33 are rotatably mounted at their lower ends at each end of the side members 14 by means of the bearing members 34, the links 33 intermediate their ends being connected by the spacer bolts 35 (Fig. 6). The upper ends of the pairs of links 33 are pivotally connected to the undersurface of the central portions of the side portions 28 of the sub-platforms by means of the bearing members 36.

As shown in Fig. 1, two pairs of laterally spaced stationary links 37 are fixedly connected to the central portion of the plate 30 and are pivotally connected at their other ends to the lift rods 38 by means of the pins 39, the lower ends of the lift rods 38 being received between each pair of spaced links 37. The upper ends of the lift rods 38 are pivotally mounted on opposite ends of the shaft 36 by means of the collars 40. The plate 13 is provided with the laterally spaced cutouts 41 (Fig. 4) which receive therethrough the links 37.

A hollow, substantially trapezoidal shaped housing 42 encases the hydraulic pump 23 between the platform 17, being open at the lower end and suitably secured to the plates 11 and 13, the housing 42 having an opening 43 which receives outwardly therethrough the pedal 24. A coil spring 44 is connected at its upper end to the top of the housing 42 and at its lower end to the foot pedal 24 whereby to automatically raise the same after it has been depressed. It will be seen that the lift rods 38 when the hydraulic pump 23 is in the lowermost position will support the sub-platform and the side portions 28 thereof slightly above the side portions 14 of the main frame with the beveled ends 29 being adapted to pass under the object to be lifted in a manner well known to those skilled in the art. In this case, the links 33 will be disposed in the inclined position of Fig. 6.

In operation, as the foot pedal 24 is pumped, the transverse shaft 26 will be raised by the hydraulic pump 23 to the dotted line position of Fig. 4, lifting the sub-platform vertically and towards the housing 42 about the bearing members 34 and 36, at which point the links 33 will be substantially vertical. Upon depressing the release pedal 25 of the pump, the platform will return promptly to its original position under the action of the springs 27.

While various changes may be made in the detail construction, it shall be understood that such changes shall be within the spirit and scope of the present invention as defined by the appended claims.

What I claim as new and desire to protect by Letters Patent of the United States is:

1. A hydraulic powered lift truck comprising, in combination, a substantially U-shaped main frame, means rotatably mounting said frame upon a supporting surface, said main frame including side portions of substantially U-shaped cross section, a sub-platform including side portions of substantially inverted U-shaped cross section adapted to nest downwardly upon said main frame side portions and a central transverse connecting portion adjacent and forwardly of the transverse portion of said main frame, first link means connecting said sub-platform with the main frame and permitting the upward movement of said sub-platform towards the central portion of said main frame, hydraulic jack means mounted upon the central portion of said main frame on a plane extending upwardly and inwardly, a transverse

shaft at the upper end of said hydraulic jack, said jack including a foot pedal for raising the same and a release pedal, spring means for returning said transverse shaft to its original position upon depressing said release pedal, lift rods pivotally connected to said sub-platform and to the ends of said shaft, said first link means comprising a pair of laterally spaced apart links pivotally connected at their lower ends to opposite ends of the side portions of said main frame between the sides thereof, spacer means connecting said links intermediate their ends, said links being pivotally connected to the under surface of said sub-platform side portions at the central portion thereof, said first links extending at an acute angle to the main frame when the sub-platform is in the lowered position extending away from the hydraulic jack, and two pairs of laterally spaced apart stationary links fixedly mounted at the central portion of the sub-platform extending toward the hydraulic jack, said lift rods at their lower ends being pivotally mounted between each pair of said stationary links, and the upper ends of said lift rods being pivotally mounted upon the ends of said shaft, the central portion of said main frame including platforms at the opposite ends thereof extending outwardly therefrom, a U-shaped handle extending upwardly from said platforms, said means rotatably mounting said main frame comprising a pair of casters rotatably mounted below said platforms, two pairs of laterally spaced wheels rotatably mounted at the other ends of the main frame side portions, a substantially trapezoidal shaped hollow

5 10 15 20 25

4 housing mounted on said main frame intermediate said platforms and enclosing said hydraulic jack, said housing having an opening receiving said pumping pedal outwardly therethrough, a second opening receiving said release pedal outwardly therethrough, and a coil spring connected at its upper end to the top of said housing having a lower end connected to said pumping pedal.

2. A hydraulic powered lift truck according to claim 1, said main frame at the central portion thereof including a U-shaped outer plate fixedly mounting said platforms at the upper ends thereof and a rectangular plate spaced longitudinally therefrom and fixedly mounting therebetween the base platform on which the hydraulic jack is mounted, the jack extending upwardly and away from said rectangular plate, said rectangular plate having a pair of laterally spaced cutouts receiving said stationary links therethrough.
